UNITED STATES PATENT OFFICE.

SETH W. JOHNSON, OF NEW YORK, N. Y.

DESIGN FOR A BANNER.

SPECIFICATION forming part of Design No. 14,256, dated September 4, 1883.

Application filed July 12, 1883. Term of patent 14 years.

To all whom it may concern:

Be it known that I, SETH W. JOHNSON, a citizen of the United States, residing at New York, in the county and State of New York, have invented and produced a new and original Design for a Banner, of which the following is a specification.

This design relates to a banner ornamented by horizontal bars or stripes and by a field containing a number of stars on the outside of an open space.

The accompanying drawing represents a face view of my banner.

In this drawing, the letter A designates an open space situated in the interior of the field B, which is ornamented by a number of stars, C. The remaining portion of the banner is composed of horizontal bars or stripes D D, of different colors.

My design is intended particularly for the American banner, in which the field B is blue, the stars C are white, and the stripes D D are alternately red and white. By the open space A in the field B a novel and distinguishing appearance is imparted to my banner. 25

What I claim as new, and desire to secure by Letters Patent, is—

The design for a banner, consisting of the horizontal bars or stripes and the field containing the open space A and the stars C C, as 30 shown and described.

In testimony whereof I have hereunto set my hand and seal in the presence of two subscribing witnesses.

SETH W. JOHNSON. [L. S.]
